UNITED STATES PATENT OFFICE.

FRANK E. JONES, OF PAWTUCKET, RHODE ISLAND, ASSIGNOR TO HEMPHILL COMPANY, OF CENTRAL FALLS, RHODE ISLAND, A CORPORATION OF MASSACHUSETTS.

PICKER MOUNTING FOR CIRCULAR-KNITTING MACHINES.

Application filed January 18, 1922. Serial No. 530,047.

To all whom it may concern:

Be it known that I, FRANK E. JONES, a citizen of the United States, and a resident of Pawtucket, in the county of Providence and State of Rhode Island, have invented 5 an Improvement in Picker Mountings for Circular-Knitting Machines, of which the following description, in connection with the accompanying drawings, is a specification, 10 like characters on the drawings representing like parts.

This invention relates to knitting machines and more particularly to circular knitting machines of small diameter.

15 In order that the principles thereof may readily be understood I have disclosed a single embodiment of the invention in the accompanying drawings wherein:

Fig. 1 is a plan view of a portion of the 20 machine and particularly of the knitting cams and narrowing pickers, the latch ring not being shown;

Fig. 2 is a view similar to Fig. 1, the latch ring being shown in functioning position; 25 and.

Fig. 3 is a view, partly in vertical section taken through the latch ring, and partly in elevation looking from the left end Fig. 1 and showing the knitting cam block and the 30 narrowing pickers.

The present or disclosed embodiment of the invention involves a circular knitting machine of the general type disclosed in the 35 patent to Hemphill No. 933,443 dated September 7, 1909, but this type of machine has been adopted merely to illustrate the nature and function of the invention and it is distinctly to be understood that the invention 40 is not limited to this particular type of machine but may equally well be used in connection with certain other types of knitting machines and especially with circular knitting machines wherein the needle cylinder remains stationary while the cams thereof 45 are revolved.

Inasmuch as my invention more particularly relates to the narrowing pickers used in heel and toe work, it is unnecessary to show the machine in detail.

50 While I am in no wise limited thereto, desirably I provide a needle carrier or cylinder mounted for rotary and also reciprocating movements in the manner fully disclosed in the said Hemphill patent. I have indicated diagrammatically at 1 in Fig. 1 the

top of the needle cylinder or carrier. Surrounding the same is a cam carrier having various cams for controlling the movements of the knitting instruments in a manner which need not be described. Desirably the 60 cam plate of the cam carrier is so mounted as to have limited vertical movements during the operation of the machine so as to vary the lengths of the loops that are being produced by the knitting instruments which, 65 in the disclosed embodiment of the invention, are latch needles, one herein shown.

I have indicated generally at 2 in Fig. 1 the knitting cam block having the several knitting cams thereon and which desirably 70 are of the same general structure as those disclosed in the said Hemphill Patent 933,443. In the present example I have represented stitch cams 3, 4 and a central guide cam 5, all of said cams being mounted in a 75 well known manner upon the cam block 2, the latter being arranged to slide upon the cam plate of the cam carrier radially with respect to the needle cylinder 1.

Heretofore so far as I am aware in machines constructed in accordance with the disclosure of the said Hemphill Patent 80 933,443 the narrowing pickers are mounted upon the cam block and they have functioned in a well known manner to elevate 85 needles at each end of the active series in the formation of heels and toes.

Such location of the narrowing pickers is 90 wholly satisfactory where the needle cylinder is of the usual diameter—such for example as $3\frac{1}{2}$ " or $3\frac{3}{4}$ ". In a machine of that diameter needle cylinder, the needles are elevated singly during reciprocating work at such a time that the latches are properly opened and are not presented, either in a 95 closed or in a partially opened condition at the opening or throat in the latch ring. Where, however, the needle cylinder is of small diameter—such for example as 2" or $2\frac{1}{4}$ "—it has been necessary heretofore to slow 100 down materially the speed of the machine in reciprocating knitting for the reason that the small diameter of the cylinder necessitates placing the pickers so close to the throat or opening in the latch ring that were 105 the needle cylinder reciprocated at the normal speed for reciprocating work, the needles would frequently be presented to the throat in the latch ring with the latches closed or partially closed, the elevating of 110

the needles by the pickers frequently actually occurring in the throat or opening of the latch ring.

I have overcome this objection in the manner hereinafter set forth and have been enabled, because of my invention, so to speed up the reciprocating work in circular knitting machines of small diameter that a single machine will produce six pairs a day 10 more than heretofore.

The latch ring is indicated at 6 and is desirably mounted as disclosed in the said Hemphill patent and is provided with a throat or opening 7 having bevelled or upwardly converging edges 8, 9. The thread guides or fingers are received in said throat in the customary manner. Herein I have represented three such guides at 10 in Figs. 2 and 3. They are respectively mounted so 15 as to be moved into and out of functioning position in a manner not herein necessary more fully to describe.

The narrowing pickers are represented at 11 and 12 in the several figures. They are 20 desirably of the general structure shown in the said Hemphill Patent 933,443 and are mounted for the usual movement upon inclined studs 13, 14 in a manner that need not be more fully described. Each of said narrowing pickers is provided with a functioning end 15, 16 such as shown in the said Hemphill patent.

When the needle cylinder is reciprocated in either direction the leading needle of the 25 active series engages one of the narrowing pickers and is thereby lifted into inactive position but retains its loop. The snapping off of such functioning narrowing picker from its engagement with said needle frequently causes the latch of such needle to 30 close or partly to close with the result that in a machine of small diameter wherein the narrowing pickers are mounted as heretofore, the said closed or partly closed latches 35 strike the opposite inclined edge 8 or 9 of the throat 7 as the case may be or else the said latches remain closed and fail to take the yarn after being picked down again into 40 action by the widening picker. This produces a hole in the fabric and in my experience very many stockings have been spoiled 45 because of this action.

It is the purpose of my invention not only 50 to prevent the formation of the said holes but also to speed up the reciprocations of the small diameter machines. This I accomplish by moving the narrowing pickers circumferentially from the knitting cams a distance proportional to the difference in diameter between the small diameter needle cylinder 55 and the normal sized needle cylinder. Otherwise stated, I compensate for the small diameter of the needle cylinder by increasing the distance between the knitting cams and 60 the narrowing pickers so as to afford time

for the narrowing pickers to function properly and to move the needles one at a time up to the inactive level before such needles can enter the throat 7 with its latch closed or partially closed as the case may be.

While the result which I have described may be accomplished in different ways I desirably provide upon the main cam block 2, supplemental supports for the narrowing pickers. To that end I have, as most clearly 75 shown in Fig. 3, provided two subsidiary or supplemental blocks or supports 17, 18 secured by one or more screws 19, 20 to the flange or base portion of the main block 2.

It is to be understood that my invention may be otherwise practiced, for example by securing the subsidiary supports or block to some other part of the mechanism than the block 2 or the said block 2 may be otherwise cast or shaped so as to support the narrowing pickers at the proper position. Preferably, however, I employ the construction described and largely for the reason that I am thus enabled to apply my invention to small diameter knitting machines now in use, it being necessary merely to construct the separate blocks 17, 18 and to secure them in position as shown in Fig. 3.

My invention in practice has been found to be exceedingly efficient and successful and I am enabled thereby to operate the small diameter knitting machine in reciprocating work at the same speed at which the larger diameter machines are customarily operated and thus to obtain the increased production stated.

It will be realized from the foregoing description that, in accordance with my invention, in small diameter machines, I start the picking up at the same point relative to the stitch cams in such small machines that the picking starts in a machine of large diameter. Inasmuch as in the small diameter machine the picker lets go quicker of the needle it is lifting, owing to the small diameter of the machine, the difficulty to which I refer has been encountered and the same is overcome by me as herein disclosed.

In the small diameter machines as constructed prior to my invention the needles were frequently elevated by the narrowing pickers directly into the throat or opening of the latch ring. In accordance with my invention, and as shown in Fig. 3, the needle, indicated at 21, is fully elevated by the picker before said needle 21 reaches the said throat or opening.

The difficulty to which I have referred has been recognized in the art as a great one and I am aware that various attempts have been made to overcome the same but wholly without success. I am enabled, by the construction described, not only entirely to overcome the difficulty but to increase the production and also at a small expense to

apply my invention to existing machines.

Having thus described one illustrative embodiment of my invention, I desire it to be understood that although specific terms are employed, they are used in a generic and descriptive sense and not for purposes of limitation, the scope of the invention being set forth in the following claims.

Claims:

- 10 1. In a small diameter, latch needle, circular, hosiery, knitting machine having a needle cylinder and a cam carrier the diameter of the former of which does not exceed substantially two and a quarter inches, a cam block on said cam carrier having knitting cams and a pair of narrowing pickers at opposite sides of said knitting cams, and subsidiary supporting blocks carrying said narrowing pickers for the purpose set forth, a latch ring having a throat with bevelled edges, one or more movable yarn guides adapted to be positioned in said throat opening, the blocks for the narrowing pickers being supported in such relative position to the opening in the latch ring that each narrowing picker functions to elevate needles to the inactive level before such needles can enter the throat of the latch ring.
- 15 2. In a small diameter, latch needle, circular, hosiery, knitting machine, a needle cylinder having a diameter not substantially exceeding two and a quarter inches, a cam carrier having a main cam block 2, stitch cams thereon, a pair of narrowing pickers at opposite sides of the stitch cams and supplemental blocks 17, 18 supporting said narrowing pickers, a latch ring having a throat with bevelled edges, one or more movable yarn guides adapted to be positioned in said throat opening, the blocks for the narrowing pickers being supported in such relative position to the opening in the latch ring that each narrowing picker functions to elevate needles to the inactive level before such needles can enter the throat of the latch ring.
- 20 3. In a small diameter, latch needle, circular, hosiery, knitting machine, a needle cylinder having a diameter not substantially exceeding two and a quarter inches, a cam carrier having knitting cams, a support for the knitting cams, a narrowing picker at one side of said knitting cams, and a supplemental support for said narrowing picker sufficiently removed from said knitting cams to secure the elevation of needles by said narrowing picker at a time substantially earlier than would be the case were said narrowing picker mounted upon the main support for the knitting cam, a latch ring having a throat with bevelled edges, one or more movable yarn guides adapted to be positioned in said throat opening, the blocks for the narrowing pickers being supported in such relative position to the opening in the latch ring that each narrowing picker functions to elevate needles to the inactive level before such needles can enter the throat of the latch ring.
- 25 4. In a small diameter, latch needle, circular, hosiery, knitting machine, a needle cylinder having a diameter not substantially exceeding two and a quarter inches, a cam carrier, a latch ring having a throat, a cam block upon said cam carrier, knitting cams upon said cam block, supplemental blocks at either side of said main block, and narrowing pickers respectively carried by said supplemental blocks, the construction and operation being such that in such small diameter machine the narrowing pickers are sufficiently removed from the knitting cams to insure the elevation of the needles thereby to the inactive level before such needles can enter the throat of the latch ring.
- 30 5. In a small diameter, latch needle, circular, hosiery, knitting machine, a needle cylinder and cam carrier, the diameter of the former of which does not exceed substantially two and a quarter inches, a latch ring having a throat 7, a cam block 2, knitting cams thereon, supplemental blocks 17, 18 at each side of the knitting cams, and narrowing pickers 11, 12 mounted upon said supplemental blocks and positioned so that they respectively elevate needles to the inactive level before said needles can enter the throat of the latch ring.
- 35 6. In a small diameter, latch needle, hosiery, circular knitting machine, wherein the needle cylinder is of a diameter not substantially exceeding two and a quarter inches, a needle cylinder and a cam carrier, the former not exceeding substantially said diameter, means relatively to rotate and to reciprocate said parts in the production of a stocking, a latch ring having a throat for the reception of a yarn guide or guides, a series of independent latch needles, knitting cams to operate said needles to take yarn and knit substantially at said guide or guides, narrowing pickers at each side respectively of said knitting cams, and means for supporting said narrowing pickers at such positions circumferentially with respect to the knitting cams that each normally functions to elevate needles respectively to the inactive level before such needles can respectively enter the said throat of the latch ring.
- 40 7. In a small diameter, latch needle, hosiery, circular, knitting machine, wherein the needle cylinder is of a diameter not substantially exceeding two and a quarter inches, a needle cylinder and a cam carrier, the former not exceeding substantially said diameter, means relatively to rotate and to

reciprocate said parts in the production of a stocking, a latch ring having a throat for the reception of a yarn guide or guides, a series of independent latch needles, knitting cams to operate said needles to take yarn and knit substantially at said guide or guides, a main block to support said knitting cams, narrowing pickers at each side respectively of said knitting cams, a supplemental block for each narrowing picker,

and means to support said supplemental block in such circumferential position with respect to the knitting cams that each of said pickers normally functions to elevate needles respectively to the inactive level before such needles can respectively enter the said throat of the latch ring. 15

In testimony whereof, I have signed my name to this specification.

FRANK E. JONES.
